UNITED STATES PATENT OFFICE.

ALBERT H. HOOK, OF NEW YORK, N. Y.

CLAMP FOR METAL STRAPS.

Specification of Letters Patent No. 26,434, dated December 13, 1859.

To all whom it may concern:

Be it known that I, ALBERT H. HOOK, of the city, county, and State of New York, have invented a new and useful Bale or Package Fastener for Fastening Metal Straps on Bales and Packages; and I do hereby declare the following to be a full, clear, and exact description thereof, referring to the accompanying drawing, in which—

Figure 1, is a perspective view of the fastener detached. Fig. 2, is a section with the two ends of the strap passed through the fastener. Fig. 3, is the cut metal wedge or nail for fastening.

My fastener or clamp is devised to effect a cheap convenient and sure fastening for thin metal binding straps for cotton and other bales and packages; it is constructed as follows: A hollow metal cylinder or cylindroid *a* (either cast iron malleable iron or wrought) is made with two flanches, one at each end at *b*, *b*.

The part between the flanches has two narrow openings from flanch to flanch opposite each other as seen at *c*. Through these openings the ends of the strap or band *d* *d* are passed and the wedged form of the nail *e* being driven between the two ends of the

strap they are thereby fastened securely. 30 To effect this most perfectly the interior of the cylinder should be somewhat conical. The point of the nail *e* should be wedge shaped so as to more readily enter between the two strap ends within the cylinder. 35

To affix this fastening when the strap is put around the package the two ends are passed through the holes in the cylinder and drawn as tight as desired; then the wedge shaped end of the nail is inserted 40 and driven through between the two parts of the strap within the cylinder, which forces them outward each way and firmly grips them immovably. To release the fastening the nail is driven back. 45

Having thus fully described my new fastening for bale and package straps what I claim therein as new and for which I desire to secure Letters Patent is—

The outer gripper *a*, and nail *e* for fastening the ends of bale and other straps constructed substantially as and for the purposes set forth. 50

ALB. H. HOOK.
